United States Patent

Des. 238,630

Patented Feb. 3, 1976

238,630

ZIPPER PULLER

Robert Grant Ammons, Sr., 1533 Northwick Road,
Baltimore, Md. 21218

Filed Sept. 11, 1974, Ser. No. 505,094

Term of patent 14 years

Int. Cl. D2—07

U.S. Cl. D2—415

FIG. 1 is a front elevational view of a zipper puller showing my new design;

FIG. 2 is a side elevational view thereof;

FIG. 3 is a perspective view thereof on an enlarged scale showing portions of the rear of the article.

I claim:

The ornamental design for a zipper puller, substantially as shown and described.
